GOLF CLUB CART HAVING RETRACTABLE
RUNNING GEARWalter J. Lowinski, Milwaukee, Wis., assignor to
Cherry-Burrell Corporation, Chicago, Ill., a
corporation of Delaware

Application May 6, 1953, Serial No. 353,399

2 Claims. (Cl. 280—41)

1

My invention relates to a golf club cart and has reference more particularly to such a cart comprising the combination of individual club receiving tubes mounted on a retractable running gear.

For many years it has been customary for golfers to keep their playing clubs in golf bags which they either carried with them on the golf course by means of a shoulder strap or which were carried for them by caddies. In recent years, however, a strong trend has developed in the direction of using carts on which conventional golf bags can be mounted and which the player pushes or pulls along with him.

The principal objects of my invention are to provide a combined golf club carrier and running gear in a single unit; to design such a combined unit having individual holders for the respective clubs; to develop a running gear which retracts compactly against the body of the club containing unit; to provide such a running gear which, when retracted, draws the wheels axially inwardly in snug relation against the body of the unit for maximum convenience in storing such as in clubhouse lockers; to devise a running gear which, when retracted, still permits rolling the cart and also enables the cart to stand erect; to provide a cooperating handle which may be folded down against the body of the cart in a manner to lock the running gear in retracted position; to develop a completely self-sufficient unit for carrying golf clubs, golf balls and accessories which is simple in design, convenient to use, and economical to manufacture, these and other objects being achieved as hereinafter described, reference being had to the accompanying drawing in which

Fig. 1 is a view from the side showing a golf club carrier embodying my invention in operating position;

Fig. 2 is a view from the rear showing the golf club carrier of Fig. 1 with the running gear retracted;

Fig. 3 is a plan view of a bracket member for holding golf club receiving tubes;

Fig. 4 is a detailed view of the running gear axle partly in section, showing the telescopic construction thereof; and

Fig. 5 is a view taken on the line 5—5 of Fig. 4.

Referring now to the drawing, the golf club carrier embodying my invention comprises a main body portion indicated generally by the reference numeral 10 and has a handle 11 adjacent the upper end of the body 10 and a re-

2

tractable running gear 12 adjacent the lower end thereof.

In a preferred form, the body 10 is composed of a vertical frame member 13, an upper bracket 14 secured to the top of said frame member 13, a lower bracket 15 secured to the opposite end thereof, and a plurality of relative elongated tubes 16 interposed between said brackets 15 and 16 in substantially parallel relation with respect to said vertical frame member 13.

The lower bracket 15 comprises a plate approximately one-half inch or more in thickness and having on one face thereof a plurality of circular recesses or seats 17 of substantially the same inside diameter as the outside diameter of the tubes 16. The seats 17 are arranged in a double row of seven each so that there are fourteen seats 17 in all, adapted to receive that number of tubes 16. At one side, the bracket 15 is provided with a socket 18 adapted to receive one end of the vertical frame member 13 and is secured thereto in any desired manner such as by means of a pin 19.

The upper bracket 14 corresponds to the lower bracket 15 in the number and arrangement of tube-receiving seats 17a. In the case of the lower bracket 15, however, each seat 17 is provided with a small drainage and ventilation hole 20, whereas in the upper bracket 14, each seat 17a is provided with an internal annular flange 21 of substantially the same width as the thickness of the walls of the tubes 16. The upper bracket 14 has a socket 18a which is secured to the vertical frame member 13 by means of a pin 19a so that the seats 17a of the upper bracket 14 face the seats 17 of the lower bracket 15. The tubes 16 are engaged at their respective ends in the seats 17 and 17a and are held securely against displacement thereby. The diameter of the flange 21 openings in the upper seats 17a is preferably about one and one-quarter inches which is sufficient to permit convenient insertion of the handles of the golf clubs 22 therethrough into the individual tubes 16 so that the club heads protrude as shown in Fig. 1.

The socket portion 18a of the upper bracket 14 is provided with a depending projection 23 having a vertically disposed face at substantially right angles to the bracket 14, said face having a plurality of annularly arranged teeth. The handle 11 is provided at one end with a corresponding projection 24 having a face with similar annularly arranged teeth adapted to mate with those on the projection 23. The

respective projections 23 and 24 are joined in face-to-face relation by means of a bolt 25 inserted therethrough, the threaded end of said bolt 25 having a wing nut 26 engaged thereon by means of which the respective projections 23 and 24 can be clamped firmly together in any selected position either in the operative position shown in Fig. 1 or in the folded position shown in Fig. 2. The engagement of the teeth on the faces of the respective projections 23 and 24 prevents displacement of the handle 11 from the selected position when the wing nut 26 is tightened.

The upper bracket member 14 may be provided with lugs 21 on the front side of the body 10—that is, on the opposite side from the vertical frame member 13—from which a suitable utility bag 28 may be suspended as shown in Fig. 1. The utility bag 28 has interior compartments for balls, sweaters, and the like, to which access may be had through the slide-fastener closures 29 as shown in Fig. 1. The lower end of the utility bag 28 may be held in place by means of tie bands 30 which may be tied around the body 10 as shown in Fig. 2.

The retractable running gear 12 consists of a pair of suitable rubber tired wheels 31 mounted on a telescoping axle 32. The telescoping axle 32 comprises an outer tubular member 33 the length of which is substantially the same as the width of the main body portion 10 of the golf club carrier, an intermediate tubular member 34 of substantially the same length as the outer tubular member 33 and inserted at one end thereof in reciprocal telescopic relation therewith, and an inner rod or tubular member 35 inserted in the opposite end of said outer tubular member 33, the inner end of said inner member 35 being telescopically engaged within the inner end of the intermediate tubular member 34 as shown in Fig. 4. The outer tubular member 33 is provided at the end through which the inner member 35 is engaged with a bushing 36 adapted to bear upon the inner member 35 so as to preserve the alignment thereof with the intermediate tubular member 34. The telescoping axle 32 is connected to the frame member 13 by means of a leg 37 which is pivotally joined to said frame member 13 by means of a fitting 38 positioned about one-third of the length from the top of the frame member 13.

The intermediate and inner members 34 and 35, respectively, are provided near their respective outer ends with fittings 39 which are affixed thereto and adapted to move inwardly therewith into abutting relation against the respective ends of the outer tubular member 33 and outwardly into extended relation as shown in Fig. 4.

The leg 37 has a ring 40 slidably mounted thereon and provided with three pivot mountings 41 to which the connecting bars 42 and 43 are pivotally secured. The connecting bars 42 are pivotally secured at their other ends to the fittings 39 and the connecting bar 43 is secured at its other end to a fitting 44 affixed to the frame member 13 at a point near the lower end thereof, preferably a distance about equal to the radius of the wheels 31 from the bottom of the frame member 13.

By virtue of this assembly and the linkages as described, the raising and lowering of the ring 40 on the leg 37 serves to simultaneously retract the running gear 12 and telescope the axle 32 or alternatively to extend said running gear 12 and project the respective intermediate and inner

members 34 and 35 outwardly with respect to the outer tubular member 33.

The respective intermediate and inner members 34 and 35 are provided with axle extensions 45 on which the wheels 31 are mounted so that the extending and telescoping of the axle 32 will propel and repel the wheels 31 as the case may be. Preferably the wheels 31 are ball bearing mounted to insure ease of operation. Also, for convenience the outer end of the handle 11 may be provided with a grip portion 46 of rubber or other suitable material.

When the described golf club carrier is used, such as on a golf course, the running gear would be in the extended position shown in Fig. 1 and the handle 11 would be raised to the position shown in the same figure. The mounting of the wheels 31 is such that when they are in extended position, the bottom of the body 10 and the wheels 31 provide a three-point support for the golf club carrier to hold it in upright position. The player may tilt the carrier into wheeling position by grasping the handle 11 and tipping the body 10 to a greater angle so as to raise the said body 10 off of the ground. When it is desired to collapse the running gear, the ring 40 is raised firmly to the position shown in Fig. 2 and the handle is lowered to the position shown in the same figure. In the collapsed or retracted position the respective wheels 31 are drawn inwardly to the respective sides of the body 10 and cooperate with the bottom of the body 10 to again provide three-point support for the golf club carrier in upright position.

The wing nut 26 may be loosened to permit lowering the handle 11 to the position shown in Fig. 2, and the wing nut 26 may then be tightened to retain the handle 11 in that position, in which case the handle 11 prevents the running gear 12 from being accidentally extended. Thus the golf club carrier embodying my invention may be folded into a compact and conveniently portable form.

My golf club carrier may be modified in various ways such as by changing the number or arrangement of the tubes 16, and it may be provided with various accessories, such as a suitable hood which can be slipped over the exposed club heads to protect them from rain, dust, and dirt.

Moreover, the features of my invention can be applied quite readily to other forms of carts either for carrying golf club bags or for other transporting purposes. Thus, while I have shown and described the golf club carrier of my invention in the preferred form, I am aware that various modifications can be made therein without departing from the spirit of my invention, the scope of which is to be determined by the appended claims.

I claim:

1 In a cart of the class described, the combination of a central body member and a retractable running gear mounted thereon, said running gear comprising a main leg hinged at one end thereof to said central body member, a telescopic axle secured in substantially perpendicular relation at the other end of said main leg, and means for concurrently retracting said main leg with respect to said central body member comprising a longitudinally slidable element on said main leg and connections to the opposed ends of said telescopic axle and to said central body member whereby, when the slidable element is moved away from said axle, the axle is telescoped and the main leg is drawn inwardly into relative alignment with said central body member.

2. In a cart of the class described, the combination of a main body member, a retractable supporting leg connected at one end thereof in pivoted relation to said main body member, and a handle similarly connected at one end thereof in pivoted relation to said main body member, said supporting leg having a telescopic axle secured in substantially transverse relation thereto at the end thereof remote from said pivoted connection, and a longitudinally slidabale element on said supporting leg and linking members interposed in pivoted relation between said slidabale element and the respective ends of said telescopic axle and said main body member, respec-

tively, and means for retaining said handle in a selected extended position with respect to said main body member and alternatively in a retracted position, in which latter position said handle engages said supporting leg and serves to hold the latter against displacement from its retracted position.
